[57] CLAIM

The ornamental design for a module for filter media, as shown.

DESCRIPTION

FIG. 1 is a perspective view of a module for filter media showing our new design;

FIG. 2 is a side elevational view thereof;

FIG. 3 is a top plan view thereof;

FIG. 4 is a cross sectional view taken on line 4—4 of FIG. 2;

FIG. 5 is a vertical sectional view taken on line 5—5 of FIG. 3; and

FIG. 6 is a vertical sectional view taken on line 6—6 of FIG. 3.

FIG. 1

FIG. 2

FIG. 3

FIG. 4

FIG. 5

FIG. 6
